(57) **CLAIM**

The ornamental design for television or monitor housing, as shown and described.

DESCRIPTION

FIG. 1 is a perspective view of the television or monitor housing;

FIG. 2 is a front view of the television or monitor housing;

FIG. 3 is a back view of the television or monitor housing;

FIG. 4 is a left side view of the television or monitor housing;

FIG. 5 is a right side view of the television or monitor housing;

FIG. 6 is a top view of the television or monitor housing; and,
FIG. 7 is a bottom view of the television or monitor housing.
The broken lines shown on the drawings are included for the
purpose of illustration only and form no part of the claimed
design.

1 Claim, 5 Drawing Sheets
